(57) **CLAIM**

The ornamental design for a desk organizer with doll, as shown and described.

DESCRIPTION

FIG. 1 is a front, top perspective view showing our new design;

FIG. 2 is a top view thereof;

FIG. 3 is a left side elevation view thereof;

FIG. 4 is a rear elevation view; and,

FIG. 5 is a right side elevation view thereof.

The broken lines showing of portions of the organizer are included for the purpose of illustrating environmental matter and form no part of the claimed design.

1 Claim, 3 Drawing Sheets

FIG. 2

FIG. 1

FIG. 4

FIG. 5
